TOY MUSICAL INSTRUMENT

Jerome L. Goldstein and Mathew A. Strumor,
New Rochelle, N. Y.

Application November 20, 1946, Serial No. 711,120

3 Claims. (Cl. 84—93)

1

This invention relates to toy whistles or wind instruments and aims to provide a novel, practical and entertaining toy of the class mentioned, which is adapted to play a tune when blown into, and which is simple in construction and inexpensive in cost of manufacture.

Another object of the invention is the provision of a turn table or the like on which one of an interchangeable plurality of what might be termed records is adapted to be mounted, in conjunction with air operated means for rotating the table simultaneously with the sounding of the notes of the tune occasioned by blowing into the instrument.

The above as well as additional objects will become apparent in the following description wherein characters of reference refer to like-numbered parts in the accompanying drawing. It is to be noted that the drawing is furnished for the purpose of illustration only and that it is neither desired nor intended to limit the invention to any or all of the specific details of construction shown.

Referring briefly to the drawing, Fig. 1 is a plan view of the toy instrument, with parts broken away and partly in section.

Fig. 2 is a sectional view taken on the line 2—2 of Fig. 1.

Fig. 3 is a sectional view taken on the line 3—3 of Fig. 2.

Referring in detail to the drawing, the numeral 10 indicates a casing or frame having the two parts or housings 11 and 12, the latter being in the form of a trumpet or tube adapted to be held in the mouth and blown into through its entrance end 14.

The housing 11 is formed integrally with the tube 12 or joined rigidly thereto, along the line 14, and is preferably provided with a flat bottom 15 and is largely substantially or approximately cup-shaped. In plan view the husing 11 is substantially circular, except for the connecting portion 20 and attached by a hinge 16 to its outer wall 17 is a substantially convex lid or cover 18. The end 19 of the tube 12 opposite the mouth end 13 is reduced substantially as shown, to provide communication between the tube 12 and the housing 11. The cover is adapted to rest frictionally in the circular opening 21 of the housing 11 when in closed position.

A horn outlet is formed in the lid 18 diametrically opposite the hinge 16 and above the opening 19. A staff 22 is rotatably mounted in the floor 11 and has at its upper end an enlargement or table 23 provided with an upwardly projecting

2

square boss 24. The cover 18 is provided with a downwardly projecting boss 25 in vertical alignment with the boss 24, but terminating, with the cover in closed position, at a short distance above the boss 24.

A pulley 26 is rigid on the staff 22. A shaft 27 is rotatably mounted in the tube 12 parallel with the staff 22, and is provided with fan blades or vanes 28; the shaft 27 extends downward into the floor 15 of the connecting housing 20, and near its lower end is provided with a pulley 29 rigid thereon. A belt 30 connects the pulleys 29 and 26.

A cylindrical hollow record 31 comprises a pair of opposed discs or walls 32 and 33, the former being provided with spaced radial slots 34 therethrough. Each of the radial slots 34 has a reed 35, of which but one is shown, anchored therein in the common manner of such wind instruments as harmonicas. The cylindrical wall 36 of the record 31 has a plurality of openings 37 therethrough, arranged so that each opening 37 is in alignment with one slot 34. Separating the slots 34 from each other are upright radial walls 38.

The slots and reeds of a given record 31 will be so constructed as, when rotated while air is passing through one reed at a time at a given point, the record will emit a tune or melody, in the well known manner. The record is removably mounted on the turn table 23, with the central square opening 39 through the record registering about the boss 24. As the reduced opening 19 is of substantially the same dimensions as the openings 37, and as, with the record in place and the lid closed the wall 36 of the record lies in the same plane as the opening 19, it is apparent that air passing from the tube 12 through the opening 19 will enter successive openings 37 as the record rotates. The air which enters an opening 37 is confined by the radial walls 38 to exit through the slot 34 between those walls, thus giving off a note which is emitted through the horn 40. The air blown into the tube 12, in addition to causing the emission of musical notes as stated, simultaneously causes the fan to rotate and thus, as is obvious, to rotate the table 23 and the record. A wall 41 is provided within the tube 12, or any other construction which attains the same end may be substituted therefor, to direct the air blown into the tube to one side of the fan 28 to facilitate rotation thereof.

Thus, each time the record makes a complete turn the tune or melody of that record will be played, and different records bearing a variety of

tunes may be provided for interchangeability with the record shown.

The actuation of the record by the means shown simplifies the operation of the toy, and the changing of a record is obviously a very simple operation. The cover boss 35 serves to keep the record from falling from the table if the toy is tilted far out of the horizontal.

Obviously, modifications may be made in form and structure without departing from the spirit 10 and scope of the invention.

We claim:

1. A toy of the class described, comprising a housing having a tube secured to one end thereof, said housing being substantially circular in plan view and having a reduced opening thereinto from said tube, said housing having a floor, a staff rotatably mounted on said floor and having a turn table thereon, said table being adapted to have a slotted and reeded wind operated musical 20 drum mounted thereon, said drum having openings through the side wall thereof and lying in the same plane as said reduced opening with said reduced opening adjacent said wall, said housing having a lid hinged thereto and having a horn outlet therein, a shaft rotatably mounted in and extending below said tube, said shaft having fan vanes thereon within said tube, pulleys on said staff and shaft, a belt trained about said pulleys. 25

2. The toy set forth in claim 1, said table having an upwardly-extending non-circular boss, said drum having a complementary non-circular recess therein, said boss being adapted to register in said recess to restrain said drum from slipping on said table. 5

3. The toy set forth in claim 1, said table having an upwardly extending non-circular boss, said drum having a complementary non-circular recess therein, said boss being adapted to register in said recess to restrain said drum from slipping on said table, said lid having a downwardly extending boss adapted to register over said first-named boss to prevent said drum from falling off 15 said table upon tilting of the toy.
